CLAIM

The ornamental design for a coffee capsule, as shown and described.

DESCRIPTION

FIG. 1 is a top-right-front perspective view showing the coffee capsule of the design;

FIG. 2 is a bottom-left-rear perspective view thereof;

FIG. 3 is a front view thereof;

FIG. 4 is a rear view thereof;

FIG. 5 is a left-side view thereof;

FIG. 6 is a right-side view thereof;

FIG. 7 is top view thereof;

FIG. 8 is bottom view thereof;

FIG. 9 is a partially enlarged view thereof, taken from FIG. 1, and shows details of the design; and,

FIG. 10 is a partially enlarged view thereof, taken from FIG. 2, and shows details of the design.

In FIGS. 1, 2, 9 and 10, the dash-dot-dash broken lines represent sectional designations that form no part of the claim.

1 Claim, 10 Drawing Sheets
